UNITED STATES PATENT OFFICE

HOWARD F. MACMILLIN, OF MOUNT GILEAD, OHIO, ASSIGNOR TO HYDRAULIC PRESS MANUFACTURING COMPANY, OF MOUNT GILEAD, OHIO

HYDRAULIC PRESS

Application filed August 31, 1929. Serial No. 389,761.

My invention relates to hydraulic presses and more particularly to improvements in valve mechanism for controlling the operation of such presses.

5 In the co-pending applications of Walter Ernst, Serial No. 296,129, filed July 30, 1928, and Serial No. 334,746, filed Jan. 24, 1929, are shown hydraulic presses which are provided with means for advancing the reciprocating platen of the press rapidly during the initial part of the pressing stroke as compared to the latter part thereof, these means including valves adapted to place the main pressing cylinder of the press in substantially 10 open communication with a source of fluid supply under static pressure such as a surge tank during the initial part of the pressing stroke, and to subsequently place the pressing cylinder in communication with a source 15 of high pressure fluid such as a pump or the like during the latter part of the pressing stroke. The first part of the pressing stroke is accomplished by the application of pressure to auxiliary or booster cylinders.

20 In other presses of generally similar construction the first part of the pressing stroke is accomplished under the influence of the weight of the platen assisted by the static head in the surge tank.

25 In both types of press it is necessary that high pressure fluid be admitted to the main pressing cylinder when the platen encounters resistance to its downward travel. This is usually accomplished by closing communication 30 between the pressing cylinder and the surge tank and by opening communication between the pressing cylinder and a high pressure pump when the platen meets the work. The platen is then returned to its 35 starting position by means of a ram or piston mounted in a platen returning cylinder, which may be of either the pull back or the push back variety.

40 Hydraulic presses having the aforesigned operating characteristics and which have been heretofore constructed have been provided with at least two separate valves for controlling admission of fluid under pump pressure to the main cylinder and to the 45 platen returning cylinder for effecting re-

ciprocations of the platen and for controlling communication of the surge tank with the main pressing cylinder for effecting the rapid prefilling of the pressing cylinder during the initial part of the pressing stroke of the 50 platen. Because of the fact that the pump pressure employed in operating such presses is quite high, usually being several thousand pounds per square inch, the valves for controlling the various application of pressure 55 are necessarily heavy and consequently expensive, and are also, because of the high pressure of the fluid which they control, susceptible to a certain amount of leakage. For these reasons it is desirable that the valves 60 controlling the application of high pressure fluid in a hydraulic press be of as simple construction as possible and also be so arranged that they may be located within the surge 65 tank.

An object of my invention is to provide a single control valve of simplified construction for controlling the application of high pressure to the pressing and platen returning cylinders of a hydraulic press and which is 70 adapted to afford relatively open communication between the surge tank and the pressing cylinder.

Another object of my invention is to provide means associated with a control valve 75 of the character described for actuating the latter in a manner to produce complete automatic operation of the press in which the platen automatically performs an indeterminate number of pressing operations, and 80 which is also adapted to actuate the valve in a manner to effect semiautomatic operation of the press, in which the platen is operated under manual control to automatically perform a complete pressing and a complete 85 return stroke, at the end of which it will come to rest in its uppermost position.

Further objects of my invention will become apparent from a reading of the following description, the appended claims, and the 90 several views illustrated in the drawings, in which:

Figure 1 is a front elevation of a hydraulic press and associated press operating hydraulic circuits embodying my invention, 100

parts of the press and certain valves being shown in section, the valves being shown in the position which they will occupy during the first part of a pressing stroke of the platen.

5 Figure 2 is a view showing in section and on an enlarged scale certain of the valves in the positions which they will occupy during the latter part of the pressing stroke of the platen, the connecting piping being removed in part for better utilization of space.

10 Figure 3 is a view similar to Figure 2 but showing the positions the valves will occupy during a return stroke of the platen.

15 Figure 4 is a view similar to Figure 2 but showing the positions the valves will occupy when the platen is at rest in its uppermost position, and

20 Figure 5 is a fragmentary or detail view of an operating rod and a lug for guiding the rod.

25 My invention may be embodied in various types of hydraulic presses, but, in the present instance, is illustrated in connection with a press A of the downward pressure type including a base 1, a press head 2 connected to the base by strain rods 3, and a reciprocatory platen 4 mounted for vertical sliding movement on the strain rods. For effecting reciprocatory movements of the platen, I provide 30 hydraulic platen actuating means comprising a pressing cylinder 5 carried by the press head, a ram 6 reciprocable in the pressing cylinder, two push back or platen returning cylinders 7, 7 each having a high pressure end 35 8 and a low pressure end 9, and pistons 10 slidably mounted in the push back cylinders and each connected to the platen 4 by a piston rod 11.

40 The pressing cylinder 5 and the high pressure ends of the platen returning cylinders are part of a high pressure hydraulic circuit, and valve means are provided in this circuit for directing fluid under pressure to the respective cylinders for effecting either automatic or semiautomatic operation of the press.

45 The high pressure hydraulic circuit includes a high pressure pump B which may be of conventional form and which is provided 50 with an intake pipe line 12 connected to a surge tank 13, and with a discharge pipe line 14 connected to a control valve C which is preferably located in the surge tank and mounted on the upper end of the pressing cylinder 5. A by-pass valve D is interposed between portions 15 and 16 of the pipe line 14 and normally provides direct communication between the control valve and the pump.

60 The control valve C includes a valve casing 17 formed with a valve chamber 18 which extends through the casing and which is closed at its opposite ends by hollow heads 19 and 20 respectively. A piston valve 21 is mounted for sliding movement within 65 the casing 17 and comprises spaced heads 22,

23, and 24 respectively, a stem 25 disposed between and connecting the heads 22 and 23, and a stem 26 disposed between and connecting the heads 23 and 24.

70 The casing 17 is provided with ports 27 and 28 respectively located adjacent opposite ends of the casing and adapted to afford relatively open communication between the surge tank 13 and the valve chamber 18. An opening 29 formed in a plug 30, removably 75 mounted in the casing 17 intermediate the port 27 and the center of the casing, provides relatively restricted communication between the valve chamber and the surge tank; and a port 31 formed in the valve casing 80 intermediate the opening 29 and the ports 28. provides direct communication between the valve chamber and an opening 32 in the pressing cylinder.

85 The pipe line 14 is adapted to communicate with the valve chamber 18 by means of a port 33 in the valve casing, and a pipe line 34 communicates at one of its ends with the high pressure ends 8 of the push back cylinders 7 and its other end is adapted to 90 communicate with the valve chamber 18 by means of a port 35.

95 When the piston valve 21 is in the position shown in Figure 1, it is desirable that the pipe line 14 communicate with the surge tank. For providing this communication, the piston valve is formed with a longitudinal passage 36 extending inwardly through the head 22 and the stem 25 and communicating at its inner end with a lateral passage 100 37 which extends from the longitudinal passage outwardly through the head 23 and communicates with an annular recess 38 formed in the head 23.

105 The valve C controls the application of pressure to the platen actuating means for effecting reciprocations of the platen, and in controlling this application of pressure the piston valve 21 is movable to three distinct positions, the first of which is illustrated in 110 Figure 1, this position being that which the valve occupies when the platen is starting a pressing stroke. When the valve is in the Figure 1 position the pressing cylinder 5 is in relatively open communication with the 115 surge tank by means of the opening 32 in the cylinder, the port 31 in the valve, the valve chamber 18, and the ports 28, and simultaneously the high pressure end of the push back cylinders has relatively restricted 120 communication with the surge tank by means of the pipe line 34, the port 35, and the small opening 29. This relatively restricted communication between the push back cylinders and the surge tank retards the descent 125 of the platen, and by using plugs having different sized openings in place of the plug 30, any desired rate of descent of the platen may be obtained. When the valve is in this position, the platen will coast downwardly 130

under the influence of its own weight assisted by the slight pressure on the ram 6 which is due to the static head of the fluid in the surge tank. During this gravitational descent of 5 the platen the discharge of the high pressure pump will pass through the pipe line 14, the passages 36 and 37 in the piston valve, and thence out through the opening 27 and into the surge tank.

10 When the platen encounters resistance to its downward travel during its pressing stroke, the piston valve 21 will be moved from its first or Figure 1 position to its second position as shown in Figure 2 in a manner to be hereinafter described. When the 15 valve is in this second position, the head 24 of the valve is positioned between the ports 28 and the port 31 thereby closing communication between the surge tank and the pressing cylinder, and the head 23 is positioned to the left of the port 33 so that fluid under pressure from the pump B will be directed into the pressing cylinder by means of the pipe line 14, the valve chamber 18, the port 25 31 in the valve casing, and the opening 32 in the cylinder. The high pressure ends of the push back cylinders will still communicate with the surge tank by means of the pipe line 34, the port 35, the valve chamber 30 18, and the opening 29. The high pressure fluid directed to the pressing cylinder will then move the platen downwardly to complete its pressing stroke.

When the platen has completed its pressing stroke, means responsive to the pressure in the main cylinder, and which will be hereinafter described in detail, move the piston valve 21 to the Figure 3 position. In this position of the valve the main press cylinder 40 5 communicates with the surge tank by means of the opening 32 in the cylinder, the port 31 in the valve casing, the valve chamber 18, and the ports 28. At the same time the discharge from the high pressure pump will be directed 45 to the high pressure end of each of the push back cylinders by means of the pipe line 14, the port 33, the valve chamber 18, the port 35, and the pipe line 34, and the platen will then perform a return stroke.

From the foregoing it will be observed that the piston valve 21 of the control valve is 55 movable to three positions for effecting a complete reciprocation of the platen. When in the first or Figure 1 position, the valve simultaneously affords relatively open communication between the surge tank and the pump, and between the surge tank and the pressing cylinders; and relatively restricted communication between the surge tank and 60 the platen returning cylinders for effecting a gravitational descent of the platen. When in the second or Figure 2 position, the valve affords communication between the pump and the pressing cylinder and also between 65 the surge tank and the platen returning cyl-

inders for completing a pressing stroke of the platen. When in the third or Figure 3 position, the valve affords communication between the pump and the platen returning cylinders and also between the tank and the pressing cylinder for effecting a return stroke of the platen.

As before stated, the control valve C is located within the surge tank, and for conveniently and efficiently operating this valve it is desirable to provide means associated therewith and controlled by other means located outside of the surge tank, to effect movements of the piston valve 21 to each of the three positions described above. For accomplishing this purpose, I provide pressure responsive means adapted to cooperate with the piston valve and mounted in the hollow heads 19 and 20. This pressure responsive means includes a plunger 39 mounted for sliding movements in a bore 40 in the head 19 and extending into a pressure chamber 41 in the head and into the valve chamber 18. The head 19 is provided with an opening 42 through which fluid under pressure is admitted to the chamber 41 in a manner to be later described, and the fluid under pressure thus admitted acts upon the plunger 39 to move the latter to the right as viewed in the drawings. Thus when the piston valve 21 of the control valve is in the Figure 2 position and fluid under pressure is admitted to the pressure chamber 41, the plunger 39 will be moved to the right and will engage the head 22 of the piston valve and move the latter to its extreme right hand position as shown in Figures 3 and 4.

For moving the piston valve 21 to the left, the head 20 is provided with aligned pressure chambers 43 and 44 which are separated by a partition 45. A plunger 46 is slidably mounted in the chamber 43, and is adapted when moved to the left to engage the head 24 of the piston valve and to thereby move the latter to the left. A plunger 47 is mounted for sliding movements in a bore 48 in the partition 45 and extends into the chambers 43 and 44, the end of the plunger which extends into the chamber 44 being provided with an enlarged head 49 adapted to engage the partition 45 to limit the movement of the plunger to the left. Openings 50 and 51 provide inlets for introducing fluid under pressure to the chambers 43 and 44 respectively.

When the piston valve 21 is in its extreme right hand position as shown in Figures 3 and 4, and pressure is admitted to the chamber 44, the plunger 47 will be moved to the left and will engage the plunger 46, thereby moving it to the left, and the plunger 46 will engage the piston valve, moving it to the left until the enlarged head 49 engages the partition 45 and arrests movement of the plunger 47 when the valve 21 has reached the Figure 1 position.

When fluid under pressure is admitted to the chamber 43, the plunger 46 will be moved farther to the left and will thus move the piston valve to its extreme left hand position as shown in Figure 2.

The by-pass valve D which is interposed in the pump discharge line 14 between the control valve and the pump serves to bypass the discharge of the pump to the surge tank when the platen approaches the end of a return stroke during semiautomatic operation of the press to thereby allow the platen to dwell in its uppermost position. It is to be understood that, when the press is operated under full automatic control, in which the platen starts a pressing stroke immediately upon the completion of a return stroke instead of coming to a state of rest at the end of the return stroke, the by-pass valve merely forms a part of the discharge line 14. However, when it is desired that the platen come to a rest at the end of a return stroke, the discharge from the pump is diverted from the control valve C and by-passed back to the tank. The by-pass valve includes a valve casing 52 formed with a valve chamber 53 and a piston valve 54 slidably mounted therein, the piston valve being provided with spaced heads 55 and 56 and with a projection 57 on the head 56 which is adapted to engage the right hand end of the valve casing for limiting the movement of the piston valve to the right. An opening 58 formed in the valve casing affords communication between the valve chamber 53 and the pipe 15, a port 59 formed in the valve casing is adapted to afford communication between the valve chamber and the pipe 16, and a port 60 in the valve casing is adapted to afford communication between the valve chamber and the surge tank.

The piston valve 54 is arranged to be moved either to the right or to the left by the application of fluid under pressure, the valve being moved to the right when fluid is admitted to the valve chamber through an opening 61 in one end of the casing and is moved to the left when pressure fluid is admitted to the chamber through an opening 62 at the opposite end thereof. When the piston valve 54 is in the position shown in Figures 1, 2, and 3, the port 60 will be covered by the head 55 of the piston valve and the pump B will communicate with the control valve C by means of the pipe 15, the opening 58 in the valve casing 52, the valve chamber 53, the opening 59, and the pipe 16. When the piston valve is moved to the left, that is, to the position shown in Figure 4, the head 56 will cover the port 59 so as to trap fluid in the pipe 34 and the high pressure end of each of the platen returning cylinders to thereby maintain the platen at rest in its uppermost position, and the discharge pipe 15 will communicate with the surge tank

by means of the opening 58, the valve chamber 53, and the port 60, so that the discharge of the pump will be diverted from the control valve C and will be by-passed into the surge tank.

For applying fluid pressure to the pressure responsive valve actuating means associated with valves C and D, I provide a low pressure hydraulic circuit in accordance with the present invention which includes means controlling the application of low pressure fluid to the pressure chambers 41, 43, 44, and to the opposite ends of the valve casing 52 of the valve D. Low pressure pilot circuits for operating main control valves are shown, described, and claimed in the copending application of Walter Ernst, Serial No. 373,985, filed June 27, 1929, and in the patent to Ernst, No. 1,763,142, issued June 10, 1930. The low pressure circuit includes a low pressure pump E which receives fluid from a tank 63 through a suction pipe 64 and discharges fluid under pressure through a pipe line 65, a pressure actuated relief valve 66 of conventional design being interposed in a branch pipe 67 which connects the pipe 65 with the tank 63. The relief valve 66 definitely limits the maximum pressure attained in the low pressure circuit and serves to by-pass fluid from the pump E to the tank 63 when pressure builds up in the low pressure circuit.

The low pressure discharge line 65 is connected to a main pilot valve F which includes a casing 67a and a chamber 68 formed therein. The pipe 65 communicates at all times with the chamber by means of an opening 69 in the casing, and a piston valve 70 having spaced heads 71 and 72 is mounted for sliding movements within the casing for controlling the application of low pressure fluid delivered by the pump E. The chamber 68 is in constant communication at its opposite ends with the tank 63 by means of a return pipe line 73 which has branches 74 and 75 connected to the casing at the opposite ends thereof. A pipe 76 connected to the casing is adapted to communicate at one of its ends with the valve chamber by means of a port 77 and communicates at its other end with the chamber 41 in the head 19 of the control valve C. A pipe 78 is adapted to communicate at one of its ends with the valve chamber by means of a port 79 in the valve casing, and communicates at its other end with the chamber 44 in the head 20 of the control valve.

When the piston valve 70 is in the position shown in Figures 1 and 2, the discharge from the low pressure pump will be directed through the pipe 65, the valve chamber 68 and the pipe 78 into the chamber 44 in the head 20. At this time the chamber 41 in the head 19 communicates with the tank 63 by means of the pipe 76, the valve chamber 68, and the pipe 73 so that the low pressure fluid in the

chamber 44 will move the plungers 47 and 46 and the piston valve 17 of the control valve to the left to the Figure 1 position to start a pressing stroke of the platen. When the piston valve 70 is moved to the left from the Figure 2 position to the Figure 3 position, the discharge from the pump E will be directed through the pipe line 65, the valve chamber 68, and the pipe line 76, and thence into the pressure chamber 41 of the control valve C, and the pressure chamber 44 will communicate with the tank 63 through the medium of the pipe 78, the valve chamber 68, the branch 75, and the pipe 73, thus effecting a movement of the piston valve 21 of the control valve to the right to its Figure 3 position for completing a pressing stroke of the platen.

Means responsive to the building up of the pressure in the pressing cylinder 5 when the platen has completed a pressing stroke is provided for moving the piston valve 70 to the left from the Figure 2 position to the Figure 3 position. This means includes a pressure chamber 80 formed in the right hand end of the valve casing 67 of the valve F, and separated from the valve chamber 68 by a partition 81, and a plunger 82 which extends through an opening 83 in the partition for engagement with the valve 70 and also into the pressure chamber 80, where the plunger is formed with a stem 84 which is of reduced diameter and which extends through and projects beyond an opening 85 in the end of the valve casing. The reduced diameter of the stem 84 provides a resultant shoulder 86 which is acted upon by fluid under pressure in the chamber 80.

The stem 84 and the plunger 82 are constantly urged to the right as viewed in the drawings by means of a coiled spring 87 interposed between the valve casing and a hand wheel 88 threadably mounted on the outer end of the stem 84. A flange 89 on the plunger 84 is adapted to engage the partition 81 and to thereby limit the movement of the plunger to the right. The chamber 80 is in constant communication with the pressing cylinder 5 through the medium of a pipe 90 which communicates at one of its ends with the chamber and at its other end with an opening 91 in the cylinder 5. When the piston valve 70 is in the position shown in Figure 2 and the platen encounters resistance to its pressing stroke, pressure will build up in the cylinder 5, and this increased or built up pressure will be transmitted to the pressure chamber 80 and will force the plunger 82 to the left. The plunger will then engage the piston valve 70 and move the latter to the left from the Figure 2 position to the Figure 3 position which will effect a movement of the piston valve 21 from its Figure 2 position to its Figure 3 position to thereby cause the platen to perform a return stroke. It

will be noted that by changing the position of the hand wheel 88, the pressure required to move the piston valve to the left may be regulated and the maximum pressure exerted by the platen thus fixed at any desired point.

For moving the piston valve 70 to the right from the Figure 3 position to the Figure 1 position, I have provided the valve with a stem 92 which projects through an opening 93 in the valve casing and which is provided at its outer end with a roller 94 adapted to be engaged by platen-actuated means when the platen approaches the end of its return stroke. The platen actuated means for moving the valve to the right includes an operating rod 95 mounted for vertical sliding movements in lugs 96 and 97 on the press head and the press base respectively, and a collar 98 on the rod which is adapted to engage the lug 97 for limiting the downward movement of the operating rod. The operating rod is urged downwardly by means of a spring 99 interposed between the lug 96 and a collar 100 on the rod. A boss 101 on the platen is provided with an opening which receives the rod for sliding movements. The boss is adapted to engage a nut 102 adjustably mounted on the rod to lift the rod when the platen approaches the limit of its return stroke. When the rod is lifted by the platen, a cam block 103 on the upper end of the rod engages the roller 94 and moves the latter, together with the stem 92 and the piston valve 70, to the right from the Figure 3 position to the Figure 1 position.

It will be observed from the foregoing that when the nut 102 is so positioned on the rod 95 as to be engaged by the boss 101 on the platen when the latter approaches the end of a return stroke, the piston valve 70 will be moved to the right from the Figure 3 position to the Figure 2 position and that this will effect the movement of the piston valve 21 of the control valve C to the left to the Figure 1 position to effect a reversal of travel of the platen and the start of another pressing stroke.

When it is desired that the press be operated semi-automatically so that the platen will come to rest at the end of each return stroke, the nut 102 is moved up and set on the rod 95 so as to not be engaged by the boss 101 when the platen moves upwardly, and other means are provided for bringing the platen to rest at the end of each return stroke. When the platen is at rest and it is desired to initiate another pressing stroke it is necessary that the piston valve 70 be moved from its Figure 3 position to its Figure 1 position. For accomplishing this movement of the valve I provide manually operable means for lifting the operating rod 95. This lifting means comprises a manually operable bell crank lever 104 pivoted to the base 1 as at 105 and having an arm 106 provided with a

rounded head 107 adapted to engage a collar 108 on the operating rod for moving the rod upwardly when the bell crank lever is swung in a counterclockwise direction. When the 5 operating rod is thus lifted under manual control the piston valve 70 will be moved to the right from the Figure 3 position to the Figure 1 position and will effect a shifting of the piston valve 21 of the control valve C to the 10 left from the Figure 4 position to the Figure 1 position which will start the platen downwardly on a pressing stroke.

From the foregoing it will be noted that 15 the pilot valve F controls this movement of the piston valve 21 of the control valve which effect reversals of the direction of travel of the platen.

It is desirable that means be provided for 20 interrupting a stroke of the platen at any time, regardless of the position of the platen, and to this end I have provided manually operable means for shifting the piston valve 70 of the pilot valve independently of the automatic or semi-automatic operation of the 25 valve. This means includes a manually operable lever 109 pivotally mounted on the press head 2 as at 110 and a lever 111 which is pivoted to the press head as at 112 and which has one arm 113 connected to one arm 114 of 30 the lever by a link 115. The other arm 116 of the lever 111 is provided with a fork 117 which cooperates with a pin 118 on the stem 92 for shifting the valve when the lever 109 is rocked. When the valves are in the position 35 shown in Figure 1 the platen will perform a pressing stroke. If it is desired to reverse the platen before it reaches the end of its pressing stroke the manually operable lever 109 will be rocked in a clockwise direction 40 which will move the piston valve 70 to the left to its Figure 3 position thus effecting a shifting of the piston valve 21 of the control valve C and a resultant reversal of the direction of travel of the platen. If it is desired 45 to reverse the platen when the latter is moving on a return stroke the lever 109 will be rocked in a counter-clockwise direction thus moving the piston valve 70 to the right from the Figure 3 position to its Figure 1 position 50 which will in turn effect a shifting of the piston valve 21 of the control valve C to its Figure 1 position and will produce a reversal of the direction of travel of the platen.

As hereinbefore stated, the first part of 55 each pressing stroke of the platen is performed when the valves are in the Figure 1 position, in which position the main pressing cylinder 5 is in relatively open communication with the surge tank so that the descent of the platen is due to its own weight assisted 60 by the static pressure in the surge tank. The low pressure circuit is provided with means responsive to the movement of the platen, but operable independently of the particular position 65 thereof for moving the control valve to

direct high pressure fluid to the pressing cylinder. This means includes a branch pipe 119 connected to the pipe 78, an auxiliary valve G connected to said branch and responsive to the pressure in the low pressure circuit, and a pipe line 120 connected to the valve G and having constant communication with the pressure chamber 43 in the head 20. The valve G comprises a valve casing 121 formed with a valve chamber 122, a piston valve 123 having spaced heads 124 and 125 mounted in the casing for sliding movements, an opening 126 in one end of the casing which affords communication between the branch pipe 119 and the valve chamber, and a spring 127 interposed between the head 125 and the other end of the casing for urging the valve to the left as viewed in the drawings. The branch pipe 119 is arranged to constantly communicate with the low pressure ends 9 of the platen returning cylinders through the medium of a branch pipe 128. The valve casing 121 is provided with a port 129 adapted to afford communication between the valve chamber and the pipe 120, and is also provided with a port 130 which is adapted to afford communication between the valve chamber and a branch pipe 131 which is arranged to constantly communicate with the low pressure return line 73. The ports 129 and 130 are so located 70 as to be disposed between the heads of the piston valve 123 when the latter is in the Figure 1 position so that normally the chamber 43 of the head 20 communicates with the tank 63 by means of the pipe 120, the valve chamber 122, the pipe 131 and the return pipe 73.

When the platen is performing the first 75 part of a pressing stroke the discharge of the low pressure pump E will be directed through the discharge line 65, the valve chamber 68 of the pilot valve F, the pipe line 78, the pipe line 128, and thence into the low pressure ends 9 of the platen return cylinders. The low pressure end of each platen returning cylinder comprises the cylinder volume included between the piston 10 and the upper end of the cylinder and it will be noted that when the platen is descending this volume is 80 constantly increasing. The rate of discharge of the low pressure pump is so regulated as to be substantially equal to the rate of increase of the volume of the low pressure ends of the platen returning cylinders so that when the platen is descending pressure will not build up in the low pressure circuit. When, however, the descent of the platen is checked because of its meeting the work, the volume of the low pressure ends of the platen returning cylinders ceases to increase at a rate equal to 85 the rate of discharge of the pump E, and pressure will build up in the discharge line 65 and the pipe line 78. When the pressure is built up to a value dependent upon the constant of the spring 127 in the valve G, the fluid 90

pressure acting upon the head 124 of the piston valve 123 will move the latter to the right against the force of the spring until the valve is in the Figure 2 position. When the valve is in this position low pressure fluid will pass from the branch pipe 119 to the pressure chamber 43 in the head 20 through the medium of the opening 126 in the valve G, the valve chamber 122, the port 129, the pipe 120 and the opening 50 in the head 20. The fluid under pressure thus admitted to the chamber 43 will move the plunger 46 to the left and the plunger will move the piston valve 21 to the left to its Figure 2 position at which time fluid under pressure from the high pressure pump will be directed to the main cylinder to complete the pressing stroke of the platen. From the foregoing it will be observed that the piston valve 123 is responsive to a change in the rate of movement of the platen for shifting the control valve to apply high pressure fluid to the pressing cylinder.

When the press is arranged for semi-automatic operation the piston valve 21 of the control valve will be in its Figure 4 position when the platen reaches the limit of its return stroke as has been hereinbefore described. In order to arrest the movement of the platen at the end of its return stroke and to maintain the platen at rest in this position I have provided means for shifting the piston valve 54 of the by-pass valve D to the left from its Figure 1 position to its Figure 4 position. This means comprises a platen actuated pilot valve H connected in the low pressure circuit for controlling the application of low pressure fluid to the valve chamber of the by-pass valve at opposite ends of the piston valve 54 thereof. The pilot valve H comprises a valve casing 132 formed with a valve chamber 133, a piston valve 134 mounted for sliding movements in the casing 132 and having spaced heads 135 and 136, and a stem 137 connected to the piston valve and projecting through an opening 138 in one end of the casing. An enlarged portion 139 on the stem intermediate the head 136 and the adjacent end of the casing, serves to limit the movement of the piston valve to the right as viewed in the drawings and a spring 140 interposed between the valve and the opposite end of the casing constantly urges the valve to the right, that is to the position shown in Figure 1.

The valve chamber 133 is at all times in communication at its central portion with the pipe line 65 by means of a branch pipe 141 which is connected to the casing at a point intermediate the heads 135 and 136 of the piston valve. The opposite ends of the valve chamber, that is those portions of the chamber lying between the ends of the casing and the heads 135 and 136 respectively, are in constant communication with the return pipe line 73 by means of branches 142 and 143 therein. The valve casting 132 is pro-

vided with a port 144 which is so located as to be disposed between the valve heads when the piston valve is in the Figure 1 position, and with a port 145 which is so located as to be disposed between the valve heads when the piston valve is in its Figure 4 position. The port 144 is adapted to afford communication between the valve chamber 133 and the left hand end of the valve chamber 53 of the by-pass valve D through the medium of a pipe 146 and the opening 61 in the valve casing 52, whereas, the port 145 is adapted to afford communication between the valve chamber 133 and the right hand end of the valve chamber of the by-pass valve D through the medium of a pipe 147 and the opening 62 in the valve casing 52. When the piston valve 134 of the valve H is in its Figure 1 position low pressure fluid will be directed from the pipe 65 through the pipe 141, the valve chamber 133 and the pipe 146 to the left hand end of the by-pass valve D, thus maintaining the piston valve 54 in the position shown in Figure 1. When the piston valve 134 of the valve H is moved to the left, in a manner to be hereinafter described, low pressure fluid from the pipe 65 will be directed through the pipe 141, the valve chamber 133 and the pipe 147 to the right hand end of the by-pass valve D, and will then move the piston valve 54 to the left to its Figure 4 position at which time high pressure pump fluid will be by-passed to the surge tank and fluid will be trapped in the high pressure end of each of the platen returning cylinders and will thereby maintain the platen at rest in its uppermost position.

For moving the piston valve 134 to the left when the platen approaches the limit of a return stroke, I have provided an operating rod 148 slidably mounted in lugs 149 and 150 on the press head and press base respectively, a collar 151 on the rod, which is adapted to engage the lug 150 for limiting the downward movement of the rod, and a spring 152 interposed between a collar 153 on the rod and the lug 149 for urging the rod downwardly. See Figures 1 and 5. A boss 154 on the platen is provided with an opening through which the operating rod 148 passes and which provides free sliding movement between the rod and the platen. A nut 155 threadably and adjustably mounted on the operating rod is adapted to be engaged by the boss 154 when the platen approaches the end of its return stroke, the rod being thereby lifted. When the rod is lifted, a roller 156 on the outer end of the stem 137 of the piston valve 134 is engaged by a cam block 157 on the upper end of the operating rod and the valve is moved to the left from its Figure 1 position to its Figure 4 position.

It is to be understood that the nut 155 can be so positioned on the operating rod 158

as to not be engaged by the platen when the latter approaches the end of a return stroke so as to permit full automatic operation of the press. When the nut is thus positioned, 5 the valve 134 will remain in the Figure 1 position at all times, and the reversals of the platen will be effected by movements of the piston valve 70 of the valve F in the manner already described. When it is desired 10 that the press operate under semi-automatic control the nut 155 can be so positioned as to produce a movement of the piston valve 134 for bringing the platen to rest at any desired point on its upward travel, that 15 is to say, by adjustably positioning the nut 155 on the operating rod, the upper limit of the platen's travel may be definitely fixed at any desired point.

20 *Operation.*

If it is desired that the press operate under full automatic control, the nut 102 will be so positioned on the rod 95 as to be engaged by the boss 101 on the platen when the latter 25 approaches the end of its upward or return stroke, and the nut 155 will be so positioned on the operating rod 148 as to not be engaged by the boss 154 on the platen when the latter approaches the end of its return stroke. The 30 pumps B and E will then be started.

Assuming that these adjustments have been made and the pumps have been started and that the platen is traveling downward, the 35 various valves will be in the positions shown in Figure 1. In these positions of the valves the pressing cylinder 5 will have relatively open communication with the surge tank through the medium of the valve member 18 in the valve C and the ports 28. At the same 40 time the high pressure end 8 of each of the push back cylinders will have relatively restricted communication with the surge tank by means of the pipe line 34, the valve chamber 18 in the control valve, and the small opening 29. The ram 6 and the platen 4 will then 45 coast downwardly under the influence of their own weight assisted by the static pressure of the fluid in the surge tank. At this time the discharge from the high pressure pump 50 B will be directed to the surge tank by means of the pipe line 14, the port 33 in the control valve, the passages 37 and 36 in the piston valve 21, the valve chamber 18, and the port 27.

55 During this gravitational descent of the platen the discharge from the low pressure pump E will be directed through the pipe line 65, the valve chamber 68 in the pilot valve F, the pipe line 78, the pipe 128, and thence into 60 the low pressure end 9 of each of the push back cylinders, and the net volume of the low pressure ends of the push back cylinders will increase at a rate substantially equal to or a little greater than the rate of discharge of 65 the pump E so that no pressure will build

up in the low pressure circuit and the valves therein will remain in the Figure 1 position.

When the platen encounters resistance to its gravitational descent and its advance is thereby checked, the net volume of the low pressure ends of the platen returning cylinders will cease to increase at a rate equal to the discharge of the pump and pressure will immediately build up in the pipe lines 65 and 78. When the pressure is built up to a predetermined point, fluid under pressure in the branch pipe 119 will act upon the piston valve 123 of the valve G and will move the piston valve to the right until the head 124 is positioned to the right of the port 129 in the valve at which time low pressure fluid from the branch pipe 119 will be admitted to the pressure chamber 43 in the head 20 of the control valve C through the medium of the valve chamber 122 of the valve G, and the pipe 120. The pressure in the chamber 43 will then move the plunger 46 and the piston valve 21 of the control valve to the left from their Figure 1 positions to their Figure 2 positions. The head 24 of the piston valve 21 will then shut off the communication between the pressing cylinder and the surge tank and high pressure fluid from the pump B will be admitted to the pressing cylinder through the pipe line 14 and the valve chamber 18 of the control valve, and the high pressure fluid will move the ram 6 downwardly to complete the pressing stroke of the platen. While the ram is being moved downwardly under high pressure, the high pressure ends of the platen returning cylinders will still communicate with the surge tank through the medium of the pipe 34, the valve chamber 18 of the control valve, and the opening 29. After the piston valve 21 of the control valve has been moved to its Figure 2 position, there can be no further flow of low pressure fluid through the pipe 120. At this time the relief valve 66 will be opened by the pressure of the fluid in the branch 67 and the discharge of the pump E will be by-passed to the tank 63.

When the platen advances on its pressing stroke the resistance presented by the work will increase and will produce a building up of pressure in the pressing cylinder 5. This increased pressure will be communicated from the cylinder 5 to the pressure chamber 80 in the valve F by means of the opening 91 in the cylinder and the pipe 90. Fluid pressure acting upon the shoulder 86 of plunger 82 will move the latter to the left against the force of the spring 87 and the piston valve 70 will thereby be moved from its Figure 2 position to its Figure 3 position. When the piston valve 70 is in this position, low pressure fluid will be directed from the low pressure pump E to the pressure chamber 41 in the head 19 through the medium of the pipe line 65, the valve chamber 68 in the valve F, and the pipe 76. At the same time

the chamber 43 in the head 20 will communicate with the tank 63 by means of the pipe 120, the valve chamber 122 in the valve G, the pipe 131 and the pipe 73; and the pressure chamber 44 in the head 20 will communicate with the tank 63 through the medium of the pipe 78, the valve chamber 68 in the valve F, the branch 75 of the return line 73, and the return line 73. The fluid under pressure in the chamber 41 will then act upon the plunger 39 to move the latter to the right which will also move the piston valve 21 of the control valve to the right from its Figure 2 position to its Figure 3 position. The 10 pressing cylinder will now communicate with the surge tank by means of the valve chamber 18 and the ports 28, whereas the high pressure end of each of the push back cylinders will communicate with the high pressure 15 pump B through the medium of the pipe line 14, the valve chamber 18 and the pipe line 34; and the platen will then perform a return stroke.

When the platen approaches the end of its 20 return stroke the boss 101 will engage the nut 102 on the rod 95 and will lift the latter, whereupon the cam block 103 will engage the roller 94 and will move the stem 92 and the piston valve 70 to the right from its Figure 3 position to the Figure 1 position. Low pressure fluid from the pump E will now be directed to the pressure chamber 44 in the head 20 of the control valve C through the medium of the pipe line 65, the valve chamber 18 in 25 the valve F, and the pipe 78. The fluid under pressure in the chamber 44 will then move the plunger 47 to the left, thus moving the piston valve 21 to the left from its Figure 3 position to its Figure 1 position. The valves 30 will then be in the same position that they occupied at the start of the pressing stroke as described above, and the platen will start another pressing stroke under the influence of its own weight assisted by the static pressure 35 of the fluid in the surge tank.

It will be apparent that when the operating mechanism is adjusted in the manner described, the press will automatically perform an indeterminate number of pressing operations and that the maximum pressure applied to the work will be uniform and not dependent upon any means whose operation is governed by the position of the platen.

If it is desired to operate the press semi-automatically, or in other words, in such a way that the platen will perform one complete pressing operation and then return to its uppermost position and stop, the nut 102 on the operating rod 95 is moved to a position in which it will not be engaged by the boss 101 when the platen moves upwardly, and the nut 155 is moved downwardly on the operating rod 148 to a position in which it 45 will be engaged by the boss 154 when the

platen approaches the limit of its upward travel.

Assuming that the platen is on its downward stroke the completion of this stroke and the start of the return stroke will be executed in the same manner as that described in connection with the full automatic operation of the press. When the platen approaches the limit of its return stroke the boss 154 will engage the nut 155 and lift the operating rod 148, whereupon the cam block 157 will engage the roller 156 and move the piston valve 134 of the valve H to the left from its Figure 1 position to its Figure 4 position. It will be noted that at this time no movement of the piston valve 70 of the valve F has taken place. Low pressure fluid will now be directed from the pump E to the right hand end of the valve chamber 53 of the by-pass valve D by means of the pipe 65, the branch pipe 141, valve chamber 143 in the valve H and the pipe line 147. At the same time the left hand end of the valve chamber of the by-pass valve D will communicate with the tank 63 by means of the pipe line 146, the valve chamber 133 of the valve H, the branch 143 of the return line 73, and the return line 73. Fluid under pressure to the right of the head 56 of the piston valve 54 in the valve D will then move the piston valve to the left from its Figure 1 position to its Figure 4 position. In this position of the valve 54, the discharge from the high pressure pump B will be by-passed to the surge tank by means of the pipe 15, the valve chamber 53 of the valve D, and the port 60 of said valve. At the same time the head 56 of the piston valve 54 will cover the port 59 and will thus shut off communication between the control valve and the valve chamber 53 of the valve D. Because of the fact that in this semi-automatic operation of the press the control rod 95 was not lifted when the platen approached the end of its return stroke, the piston valve 70 of the valve F and the piston valve 21 of the valve C remained in their Figure 3 position when the platen reached the end of its return stroke. Fluid will now be trapped in the high pressure end 8 of each of the platen returning cylinders and the pipe line 34 by means of the heads 22 and 23 of the piston valve 21 and by the head 56 of the valve 54 which now covers the port 59. This entrapped fluid in the platen returning cylinders will prevent the platen from coasting downwardly and will maintain the latter in its uppermost position. If, however, there should be some leakage in the system so that some of the entrapped fluid should escape from the platen returning cylinders, the platen will coast downwardly until the rod 148 has been lowered sufficiently to permit the spring 140 of the valve H to move the piston valve 134 to the right to its Figure 1 position. When this movement of the valve has taken place, low pressure fluid will be directed from the pipe 141 to the left

hand end of the by-pass valve, which will move the piston valve 54 therein to the right to its Figure 1 position. The platen will then be returned to the uppermost position and 5 will then be again brought to rest in the manner already described. Thus, although the platen may move downwardly to some slight extent, it is apparent that it will be automatically maintained at or near its uppermost 10 position until it is desired that it perform another stroke.

To cause the platen to perform another complete reciprocation, the bell crank lever 104 is rocked in a counterclockwise direction. 15 This will raise the rod 95 and move the piston valve 70 to the right from its Figure 4 position to its Figure 1 position. This will in turn admit low pressure fluid to the pressure chamber 44 for moving the piston valve 21 20 of the control valve to the left from its Figure 4 position to its Figure 1 position and the platen will then start downwardly upon another pressing stroke.

It is to be understood that the manually 25 controlled means for moving the piston valve 70 of the valve F, that is the operating lever 109 and associated mechanism, is operable for interrupting the movement of the platen while the latter is performing either a pressing or a return stroke regardless of whether 30 the press is arranged for full automatic operation or for semi-automatic operation. The lever 109 thus provides means for interrupting the movement of the platen in case of 35 emergencies and also for controlling the reciprocations of the platen when it is desired that each stroke thereof be under the control of the operator.

It is to be understood that the construction 40 and arrangement of parts shown in the drawings is illustrative rather than definitive. As will be obvious to those skilled in the art, other fluid pressure mediums, such as compressed air, steam or the like could be employed instead of a liquid medium for operating the control valve C. Although I have 45 illustrated a press provided with a platen especially adapted for performing compressing operations, it is to be understood that the 50 invention described herein may be embodied in presses used for punching, forging, shearing or other like purposes and that the term "platen" is intended to cover any tool, die or other appliance with which a press embodying my invention might be provided. Other modifications in construction and arrangement of parts may be also made without departing from the scope of my invention 55 which is defined in the claims.

60 I claim as my invention:

1. The combination with a hydraulic press including a reciprocatory platen, a pressing cylinder, and a platen returning cylinder; of a surge tank; a pump; means forming with 65 said pressing cylinder, said platen returning

cylinder, said surge tank, and said pump a hydraulic circuit; and a valve operatively connected in said circuit for controlling the movements of said platen, said valve being movable to three positions, in the first of 70 which positions said valve affords communication between said surge tank, said pressing cylinder, said platen returning cylinder, and said pump for permitting a gravitational descent of the platen, in the second of which 75 positions said valve affords communication between said pump and said pressing cylinder and also between said platen returning cylinder and said surge tank for completing a 80 pressing stroke of the platen, and in the third of which positions said valve affords communication between said pump and said platen returning cylinder and also between said tank and said pressing cylinder for effecting a return stroke of the platen. 85

2. The combination with a hydraulic press including a reciprocatory platen, a pressing cylinder, and a platen returning cylinder; of a surge tank; a pump; means forming with 90 said pressing cylinder, said platen returning cylinder, said surge tank, and said pump a hydraulic circuit; a valve operatively connected in said circuit for controlling the movements of said platen, said valve being movable to three positions, in the first of 95 which positions said valve affords communication between said surge tank, said pressing cylinder, said platen returning cylinder, and said pump for permitting a gravitational descent of the platen, in the second of which 100 positions said valve affords communication between said pump and said pressing cylinder and also between said platen returning cylinder and said surge tank for completing a 105 pressing stroke of the platen, and in the third of which positions said valve affords communication between said pump and said platen returning cylinder and also between said tank and said pressing cylinder for effecting a return stroke of the platen; pressure responsive means associated with said 110 valve for moving the latter; and means for applying fluid pressure to said pressure responsive means.

3. The combination with a hydraulic press including a reciprocatory platen, a pressing cylinder, and a platen returning cylinder; of a surge tank; a pump; means forming with 115 said pressing cylinder, said platen returning cylinder, said surge tank, and said pump a hydraulic circuit; a valve operatively connected in said circuit for controlling the movements of said platen, said valve being movable to three positions, in the first of 120 which positions said valve affords communication between said surge tank, said pressing cylinder, said platen returning cylinder, and said pump for permitting a gravitational descent of the platen, in the second of which 125 positions said valve affords communication

between said pump and said pressing cylinder and also between said platen returning cylinder and said surge tank for completing a pressing stroke of the platen, and in the 5 third of which positions said valve affords communication between said pump and said platen returning cylinder and also between said tank and said pressing cylinder for effecting a return stroke of the platen; pressure responsive means associated with said valve for moving the latter; and means for automatically applying fluid pressure to said pressure responsive means to move said valve to any of said positions.

4. The combination with a hydraulic press including a reciprocatory platen, a pressing cylinder, and a platen returning cylinder; of a surge tank, a pump; means forming with said pressing cylinder, said platen returning cylinder, said surge tank, and said pump a hydraulic circuit; a valve operatively connected in said circuit for controlling the movements of said platen, said valve being movable to three positions, in the first of 20 which positions said valve affords communication between said surge tank, said pressing cylinder, said platen returning cylinder, and said pump for permitting a gravitational descent of the platen, in the second of which 25 positions said valve affords communication between said pump and said pressing cylinder and also between said platen returning cylinder and said surge tank for completing a pressing stroke of the platen, and in the 30 third of which positions said valve affords communication between said pump and said platen returning cylinder and also between said tank and said pressing cylinder for effecting a return stroke of the platen; means 35 associated with said valve and operable when the platen encounters resistance to its pressing stroke for moving said valve from said first position to said second position; and means associated with said valve and responsive to the pressure in said circuit for moving said valve from said second position to said third position.

5. The combination with a hydraulic press including a reciprocatory platen, a pressing cylinder, and a platen returning cylinder; of a surge tank; a pump; means forming with said pressing cylinder, said platen returning cylinder, said surge tank, and said pump a hydraulic circuit; a valve operatively connected in said circuit for controlling the movements of said platen, said valve being movable to three positions, in the first of 40 which positions said valve affords communication between said surge tank, said pressing cylinder, said platen returning cylinder, and said pump for permitting a gravitational descent of the platen, in the second of which 45 positions said valve affords communication between said pump and said pressing cylinder and also between said platen returning cylinder and said surge tank for completing a pressing stroke of the platen, and in the third of which positions said valve affords communication between said pump and said platen returning cylinder and also between said tank and said pressing cylinder for effecting a return stroke of the platen; means associated with said valve and operable when the platen encounters resistance to its pressing stroke for moving said valve from said first position to said second position; and means associated with said valve and responsive to the pressure in said circuit for moving said valve from said second position to said third position.

6. The combination with a hydraulic press including a reciprocatory platen, a pressing cylinder, and a platen returning cylinder; of a surge tank; a pump; means forming with said pressing cylinder, said platen returning cylinder, said surge tank, and said pump a hydraulic circuit; a valve operatively connected in said circuit for controlling the movements of said platen, said valve being movable to three positions, in the first of 50 which positions said valve affords communication between said surge tank, said pressing cylinder, said platen returning cylinder, and said pump for permitting a gravitational descent of the platen, in the second of which 55 positions said valve affords communication between said pump and said pressing cylinder and also between said platen returning cylinder and said surge tank for completing a pressing stroke of the platen, and in the third of which positions said valve affords communication between said pump and said platen returning cylinder and also between said tank and said pressing cylinder for effecting a return stroke of the platen; and means operatively connected in said circuit and adapted to place said pump in communication with said tank and to simultaneously trap fluid in said platen returning cylinder when the platen reaches the end of a return stroke.

7. The combination with a hydraulic press including a reciprocatory platen and hydraulic platen actuating means for reciprocating the platen; of a surge tank; a high pressure pump; means forming with said platen actuating means, said surge tank, and said pump a high pressure hydraulic circuit; a single valve operatively connected in said circuit for controlling the movements of said platen, said valve controlling communication between said tank and said platen actuating means and also between said pump and said platen actuating means; pressure responsive valve actuating means associated with said control valve; a source of low pressure fluid; means connecting said source of low pressure fluid to said valve actuating means.

sure fluid to said valve actuating means; and means interposed in said connecting means for controlling the application of low pressure fluid to said valve actuating means.

5. 8. The combination with a hydraulic press including a reciprocatory platen, a pressing cylinder, and a platen returning cylinder; of a surge tank; a high pressure pump; means forming with said pressing cylinder, said 10 platen returning cylinder, said surge tank, and said pump a high pressure hydraulic circuit; a control valve operatively connected in said circuit for controlling the movements of said platen, said valve being movable to three 15 positions, in the first of which positions said valve affords communication between said surge tank, said pressing cylinder, said platen returning cylinder, and said pump for permitting a gravitational descent of the platen, 20 in the second of which positions said valve affords communication between said pump and said pressing cylinder and also between said platen returning cylinder and said surge tank for completing a pressing stroke of the 25 platen, and in the third of which positions said valve affords communication between said pump and said platen returning cylinder and also between said tank and said pressing cylinder for effecting a return stroke of 30 the platen; pressure responsive valve actuating means associated with said control valve; a source of low and variable pressure fluid; means connecting said source of low pressure fluid to said valve actuating means; a 35 valve interposed in said connecting means and operable upon an increase in pressure of said low pressure fluid for admitting low pressure fluid to said valve actuating means to move said control valve from said first 40 position to said second position; a pilot valve interposed in said connecting means and responsive to an increase in pressure in said high pressure circuit for admitting said increased low pressure fluid to said valve actuating 45 means to move said control valve from said second position to said third position; said pilot valve being adapted to admit low pressure fluid to said valve actuating means to move said control valve from said third 50 position to said first position; and means for automatically actuating said pilot valve when the platen approaches the end of a return stroke.

9. The combination with a hydraulic press 55 including a reciprocatory platen, a pressing cylinder, and a platen returning cylinder having a high pressure end and a low pressure end; of a high pressure pump; means forming with the pressing cylinder, the high 60 pressure end of the platen returning cylinder, and the pump, a high pressure hydraulic circuit; a reciprocable piston in said platen returning cylinder, a connection between said piston and said platen; valve 65 means in said circuit for controlling the ad-

mission of high pressure fluid to said pressing cylinder and to the high pressure end of said platen returning cylinder; valve actuating means associated with said valve means; a low pressure pump; hydraulic connections 70 between said low pressure pump, said valve actuating means, and the low pressure end of said platen returning cylinder; means in said low pressure circuit for directing the discharge of said low pressure pump to the 75 low pressure end of said platen returning cylinder during the initial part of a pressing stroke of the platen; and pressure responsive means in said low pressure circuit and associated with said valve actuating means and operable when the platen encounters resistance to its pressing stroke for moving said control valve to effect communication between said high pressure pump and said 80 pressing cylinder.

10. The combination with a hydraulic press including a reciprocatory platen, a pressing cylinder, and a platen returning cylinder having a high pressure end and a low pressure end; of a high pressure pump; means forming with the pressing cylinder, the high pressure end of the platen returning cylinder, and the pump, a high pressure hydraulic circuit; a reciprocable piston in said platen returning cylinder; a connection between said piston and said platen; valve means in said circuit for controlling the admission of high pressure fluid to said pressing cylinder and to the high pressure end of said platen returning cylinder; valve actuating means associated with said valve means; a low pressure pump; hydraulic connections between said low pressure pump, said valve actuating means, and the low pressure end of said platen returning cylinder; means in said low pressure circuit for directing the discharge of said low pressure pump to the low pressure end of said platen returning cylinder during the initial part of a pressing stroke of the platen; and pressure responsive means in said low pressure circuit and associated with said valve actuating means and operable when the platen encounters resistance to its pressing stroke for moving said control valve to effect communication between said high pressure pump and said pressing cylinder, the rate of discharge of said low pressure pump being substantially equal to the rate of increase of volume of the low pressure end of said platen returning cylinder during the initial part of each pressing stroke of the platen.

11. The combination with a hydraulic press including a reciprocatory platen and hydraulic platen actuating means for reciprocating the platen; of a surge tank; a pump; means forming with the platen actuating means, surge tank, and pump a hydraulic circuit; a valve in said circuit having a single movable element which is operable to alone 125

control communication between said tank and said platen actuating means, and also between said pump and said platen actuating means; means operatively connected to said valve for automatically operating said element to effect a complete reciprocation of said platen; and manually controlled means for moving said movable element to interrupt the movement of said platen during a pressing stroke irrespective of the position thereof.

10 In testimony whereof, I have hereunto subscribed my name.

HOWARD F. MACMILLIN.
